CUP-PAstry-MAKING MACHINE AND METHOD AND MEANS FOR EXTRACTING THE
CONTENTS THEREOF.

Application filed March 16, 1926. Serial No. 95,100.

My invention relates to the art of cup pastry molding and baking (such as ice cream cones, patty cups and the like), and it particularly relates to machines of the 5 type employing split female molds and cores.

Primarily the invention has for its object to provide a new method of extracting the baked article from the female mold without using the core as an extraction 10 finger, and also to provide an improved mold operating mechanism by which the method referred to, mechanically may be conducted (although it should be understood the method can be carried out manually if desired, 15 and as to the method I do not wish to be limited to the use of any specific or particular apparatus).

Generically the invention resides, primarily, in separating the female mold sections 20 in a peculiar manner (after removal of the cores) while holding the article in a substantially fixed position without the necessity of using cores, dummy cores, cupped plates, extractor bars, or any other extractor 25 device which is to engage, mechanically, any portion of the side of the article or the edge of the article around the mouth to exert lateral force or restraint on the article (i. e. in a direction normal or approximately 30 normal to its axis); in other words, my present invention resides in moving the mold sections apart by a simultaneous separating and downward motion, while holding the article from lowering or rising, by suitable 35 restraining means acting in the direction of the axis of the article, thereby permitting a detachment of the female mold surfaces from the article while leaving the article free to move bodily laterally (so far as such 40 restraining means may be concerned) but not to rise or fall in substantial degree until adhesion between article and female mold shall have been broken, after which the female mold sections are further separated to 45 permit the article to drop through.

In its generic mechanical phase the invention resides in providing a suitable mechanism for effecting the restraint and the mold movements in such manner and sequence as to carry out the method which constitutes the principal part of my invention. 50

More specifically, in carrying out my method mechanically, I prefer to provide

the female mold sections with a supporting means to permit the same to be initially separated by a hinge-like movement or book-fashion, as it may be termed, with the axis at the bottom, while means are provided to constitute an abutment at the mouth of the article against which the article will come 55 into contact if it tends to elevate while the female mold sections are undergoing their initial separatory movement to effect a stripping of the article from the female mold walls; means are also provided to bring the 60 restraining instrument into operative association with the female mold at proper times; means are also provided to separate the female mold sections in the manner stated to release the article and permit it to pass 65 through.

In its more detailed nature my invention includes those novel features of construction, operation and arrangement of parts, all of which will be first fully described, 70 then be specifically pointed out in the appended claims, reference being had to the accompanying drawings, in which:

Figure 1 is a plan view of a portion of a rotary wheel type machine employing my 75 invention.

Figure 2 is a cross section of a mold unit at the station preceding the extracting station and showing the core in process of removal.

Figure 3 is a view similar to Figure 2 taken at the extracting station, the restraining plate having been lowered into association with the female mold sections and the female mold sections having undergone their 80 preliminary or cracking movement.

Figure 4 is a view similar to Figures 2 and 3 showing the mold sections fully separated at the extracting station, showing the article dropped in dotted lines, and showing the 85 article just prior to its release from contact with the restraining plate.

Figure 5 is a vertical longitudinal section on the line 5-5 of Figure 2 showing the position of parts, however, just prior to 90 giving the female mold its preliminary opening movement or cracking.

Figures 6 and 7 are detail views of the lower and upper guideways.

In the drawings, I have illustrated one 95 embodiment of my invention in a machine of

the rotatable table type, though it may readily be adapted to machines with other types of carriers.

Like numerals and letters of reference indicate like parts in all the figures of the drawings, by reference to which it will be seen that 1 designates the inner and outer concentric rims of a rotatable wheel or table of a type now well known and between 10 which rims the several mold units are mounted. These units each comprise complementary sections 2 having the usual die cavity between them and constituting the female mold. Cores 3 secured on a bar 4 that is 15 carried on a vertical slideable standard 4^a which is mounted in a slideway 6 on the inner or back face of the rim 1 cooperate with each female mold unit. Each standard 4^a carries a roller 4^b with which the core bar 20 raising and lowering cam track 5 cooperates to effect the removal and replacement of the cores at proper intervals.

Each rim 1 has upper and lower slideways 7 and 10 respectively, one pair adjacent each 25 end of each mold half. The upper slideways 7 have arcuate portions 8 struck with their centers or axes at 30 and they have straight or horizontal portions 9; the lower slideways 10 have arcuate portions 11 struck 30 from the same centers or axes 30 and they have inclined portions 13 and straight or horizontal portions 12 as best indicated in Figures 6 and 7.

Each mold half has an upper guide and 35 supporting roller 16 and a lower guide and supporting roller 17 at each end, these rollers operating respectively in the slideways 7 and 10.

Mold fulcrum lugs 14 having central 40 peaks 15 are provided on each rim 1 and serve as rests for the mold sections in lieu of the lower rollers 17 when the mold sections are locked together.

18 designates mold opening and closing 45 rock-shafts which carry the cams 19. The latter are adapted to engage the mold ribs 2^a in pushing the sections together and locking the same as a toggle, pins 20 being carried by the cams 19 to work in slots 21 on the molds to effect the cracking or initial 50 separation and the final separation of the female mold sections. The shafts 18 are rocked by levers 22 connected together by toggle links 23 which also are pivoted together to a slide 24 mounted in a guide 25 on the outer rim 1 of the wheel. The slide 24 carries a roller 26 by which it may be moved up and down at proper times.

A lever 27 may be provided, operated by a 60 suitably timed cam through a connecting rod 28 to break the toggle and operate the mold sections; a stationary cam track 29 may be employed under which the roller 26 passes upon leaving the extracting station to force 65 it down again and close and lock the female

sections together. As the mechanism for operating the toggle links is of a well known type and per se is not a part of my invention, further illustration thereof is thought to be unnecessary.

The extreme lower edges of the female mold sections which meet at the medial vertical longitudinal plane of the unit constitute a fulcrum or axis 30, and which, when the mold is closed, rest on the peak 15 of the fulcrum lugs 14, the bottom surfaces 31 of the mold sections being upwardly inclined as shown so that the rollers 17 may protrude slightly below the same.

Mounted in slide 33 which operates up 80 and down in a fixed slideway 35 that is located on a stationary frame 34 is, what I term, a restraining plate. This plate is normally held elevated above the top level of the die cavity by riding on the raised portions or holding up cams 36 of the rims 1 but which may drop down close to the mouth of the cavities when the cavities come beneath the plate. While the weight of the plate may be found sufficient for the purpose, nevertheless if desired, plate lowering means 37 may be carried by the rims 1 to assist this lowering movement at the proper time.

If desired the plate 32 may have an air 95 duct 38 with ports 39 to align with each mold section of a unit, this duct being connected with a source of suction through a control valve 40 normally closed, but whose stem 41 is adapted to be pressed to the open 100 position by the downward movement of the plate 32 so as to create a reduced air pressure beneath the restraining plate which will tend to suck or hold the articles, when released, to the plate.

I may also connect the duct 38 with a source of pressure through a control valve 42 whose stem 43 is designed to be pressed to the open position on the upstroke of the plate 32 to allow air under at least atmospheric pressure, to communicate with the interior of the baked articles beneath the restraining plate at the proper time to break the vacuum and permit those articles to fall out or be impelled downwardly through between the open female molds. The connection between the duct 38 and the valves 40 and 42 may be made by flexible hose 44. Other means may be provided for operating the valves 40 and 42 at proper intervals than the means just described and I do not wish to be limited specifically to that means.

In this application I have disclosed no mechanism for effecting rotation of the wheel, no means for charging the molds, no means for locking the cores down, no trimming mechanism, etc., as any suitable mechanism of the kind now common in the art may be used for the purposes stated, since my invention deals principally, if not wholly, with

the extraction procedure of a pastry making machine of the kind stated and I therefore do not deem it necessary to show and describe such well known mechanism.

6 In practicing the method which constitutes the basis of my invention, after removal of the core from the closed female mold, I first place a restraining member 32 over the mold mouth as closely as practicable (preferably in contact with the article) and then separate the sections preliminarily by hinge movement around the axis 30 from the position shown in Figure 2 to that shown in Figure 3 (i. e. open the mold 10 sections book-fashion). This cracks the mold and opens it far enough to strip the article from adhering to the mold surfaces. By reference to the drawings it will be noticed that should the article adhere to one 15 female mold section or the other during the cracking process it would have a tendency to tilt with that mold section which would throw the upper edge or mouth of the article above the horizontal plane of the 20 lower face of the restraining plate, the restraining plate being there, however, it prevents such movement of the article with the result the article will be stripped or peeled from the sections of the female mold to 25 which it is adhering. After the article has become detached from the female mold in this way the mold sections are then moved farther apart a distance sufficient to permit the article to drop down and out. In order 30 to insure a uniform dropping of the article and prevent it falling crosswise between the open sections I may hold the article temporarily to the restraining plate by suction, breaking the suction when the mold sections 35 have separated sufficiently and even increasing the air pressure to effect a momentary blow into the article, thereby insuring, in a positive manner, the uniform travel downwardly through the open mold (into the 40 trimmer tubes if such are used).

50 In operating the mechanism which I have devised for the purpose of carrying out my method mechanically the same is manipulated as follows: assume the female mold to be in the closed position just preceding the extraction station (the end of the baking interval). After the core is removed by ascending the cams 5 and passing from position shown in Figure 2 to the extracting 55 station in Figure 3, when the unit arrives at the extracting station the roller 26 will have come into operative relation with the lever 27, which lever is then operated to raise the roller 26, the initial movement being indicated in Figure 3. This causes the locking pressure on the female mold sections to be released; as the centers of gravity of the mold sections are, of course, to either side of the mid-plane which contains the axis 30, the natural tendency of the female mold sec-

tions, when unlocked, will be to open as a book. This tendency is augmented by the pins 20 pulling the sections apart, see Figure 3. Before the mold sections are cracked, however, the restraining plate 32 will have 70 been lowered to position over the female mold, see Figure 3, and held there either by its own weight or by the assistance of the hold-down cams hereinbefore referred to, so that the pastry articles cannot rise in the 75 mold. Therefore by the time the mold sections shall have been opened to the extent indicated in Figure 3 the article will have become detached therefrom.

It will be noticed that as the mold sections 80 begin to crack apart the rollers 17 will be in engagement with the arcuate portions 11 of the guideways 10; this will aid in holding the lower edges of the mold together while the upper edges are moved apart. By the 85 time, however, the sections reach the position of Figure 3 the rollers 17 will have engaged the bottoms 12 of the guideways. Therefore on further separation of the mold sections their rollers 16 and 17 will ride on the horizontal portions of the guideways (thus reducing friction) until the fully open position (Figure 4) is reached. In this manner the wear on the lower mold 90 edges at 30 is reduced to a minimum. 95

When uniform dropping of the articles is not a consideration, no means need be provided to hold the articles to the plate 32 after they have been detached from the female mold walls, they may be permitted 100 to fall at will. However, as in many instances it is desirable to trim the article, it becomes helpful to have them fall in a uniform way as along the direction of their axes. This may be effected by use of suction through the duct 38 and ports 39. As the suction is not required for detaching purposes a very light suction is all that is necessary to overcome the weight of the baked articles. This suction is allowed to remain 105 in action until the mold sections have opened a distance sufficient to permit the articles to fall clear; then the suction is discontinued or broken and the article freed, or a pressure in excess of atmospheric may be passed 110 through the ports 39 outwardly to blow the articles downwardly and thus assist in the rapidity at least of their passage through the open molds. 115

The female mold sections are closed by the reverse motion of the shafts 18, the mold sections being carried freely on the rollers 16 and 17 until the lower edges at 30 come together, then these edges constitute a hinge axis and the sections swing to the finally 120 closed position book-fashion and are locked by the cam levers and toggle links.

Other devices may be provided to lock and unlock, close and separate, the mold sections than the ones herein described, as I 125

have intimated, for mechanisms are known in the art which are the equivalent of these, and I do not wish to be understood as limiting my invention to the embodiment of the specific mechanism employed in the parts 18 to 28 inclusive.

Where the article is formed with a head sheet the mold units will, of course, be separated somewhat farther than is necessary where no head sheet is formed, but the formation of a slight head sheet will not be detrimental to the operation of my machine or the carrying out of my method, but rather it will be helpful in that it will give a greater area of flat contact between the top of the article and the restraining plate and thus distribute the detaching force over a larger area.

It should be understood that as the wheel turns to move the mold unit away from the extraction station the plate 32 will ride up the rear cam 36 and rise, thereby engaging valve stem 43 to open the valve 42 before the mold section hits the cone.

From the foregoing description, taken in connection with the accompanying drawings, it is thought that my method and the mechanism which I have devised for carrying out that method will be clear to those skilled in the art.

What I claim is:

1. The method of extracting cup pastry from split female molds after removal of the cores therefrom, which consists in first opening the female mold sections book-fashion while holding the pastry against tilting or moving over with a mold section, thereby stripping the pastry from the female mold sections, and subsequently moving the mold sections a sufficient distance apart to permit the pastry to drop out.

2. The method of extracting cup pastry from split female molds after removal of the cores, which consists in opening the female mold sections by a pivotal motion around an axis at the bottom of the mold and in the plane of the split, whereby to separate the upper or mouth ends of the mold wider than the point or bottom of the mold cavity while holding the pastry by engagement with the upper face of the same against tilting on its axis, and subsequently moving the female mold sections bodily apart a distance sufficient to permit the pastry to drop through.

3. The method of extracting cup pastry from split female molds after removal of the cores, which comprises first the tilting of the female mold sections apart to open the top of the cavity wider than the bottom of the cavity, while holding the pastry from tilting with a mold section so as to keep the upper edge of the pastry in a plane approximately normal to the axis of the mold cavity 60 when the female mold sections are closed,

and thereafter moving the female sections bodily apart a distance sufficient to permit the pastry to drop through.

4. The method of extracting cup pastry from split female molds after removal of the cores, which consists in engaging the upper or top surface of the pastry to hold the pastry from rising in the mold and separating the female mold sections from one another book-fashion until the pastry has become detached from the female mold walls, and then moving the female mold sections from one another a distance sufficient to permit the pastry to drop out.

5. The method of extracting cup pastry from split female molds after removal of the cores, which consists in engaging the upper face of the pastry to prevent its rising, and opening the female molds by movement downwardly and away from one another while holding the pastry from dropping until it has become detached from the walls of the female mold, and thereafter moving the mold sections still farther apart a distance sufficient to permit the pastry to drop, and releasing the pastry so that it may drop out of the mold.

6. The method of extracting cup pastry from split female molds after removal of the cores, which consists in creating a partial vacuum above and within the pastry while holding the pastry against upward movement, and separating the female molds by simultaneous movement away from the axis of the cavity and downwardly, and after the molds have been opened far enough to permit passage of the pastry, increasing the pressure within and above the pastry to release it and permit it to fall through between the open mold sections.

7. In cup pastry making machines, a pair of female mold sections and a core therefor, means for withdrawing the core from the article within the mold sections, means for separating said sections by a downward and outward motion, means to engage the article at its top to arrest it against following over with a mold section, said separating means having provision upon further movement to open the mold sections apart a distance sufficient to permit the article to drop through.

8. In cup pastry making machines, a pair of female mold sections and a core therefor, means for withdrawing the core from the article within the mold sections, means for separating said sections by a downward and outward motion, around an axis located beneath the bottom of the mold cavity, means to engage the article at its top to arrest it against following over with a mold section, said separating means having provision upon further movement to open the mold sections apart a distance sufficient to permit the article to drop through.

9. In cup pastry making machines of the

gaged by the mouth of the baked article during the rotation of the female mold sections to arrest the article from tilting over with a mold section to which it may be adhering, 5 thereby to strip the article from said mold section, said last named means comprising an arresting plate and mechanism for placing the plate into and removing it from operative association with the female mold at 10 times, means to create a suction beneath said plate to cause the article to tend to adhere to said plate after the plate has been placed into operative association with the female mold and during at least the initial portion 15 of the time the female sections are opening, and means to restore pressure, at least to atmospheric, between plate and article after the mold sections have been separated a distance sufficient to discharge the article.

20 16. In cup pastry making machines of the type employing sectional female mold units and cores; the combination with a mold carrier, a pair of female mold sections, said carrier having guideways and said sections 25 having members associated with said guideways, said guideways including arcuate and straight way portions, whereby as such sections are separated they will first open at the top and then move bodily away from one 30 another, means for separating said sections and bringing them together again at intervals.

17. In cup pastry making machines of the type employing sectional female mold units 35 and cores; the combination with a mold carrier, a pair of female mold sections, said carrier having guideways and said sections having members associated with said guideways, said guideways including arcuate and straight way portions, whereby as such sections are separated they will first open at the top and then move bodily away from one another, means for separating said sections and bringing them together again at intervals, 40 means to support said sections at a place as a pivot during the initial opening movement and while the sections are closed together.

18. In cup pastry making machines of the type employing sectional female mold units 50 and cores; the combination with a mold carrier, a pair of female mold sections, said carrier having guideways and said sections having members associated with said guideways, said guideways including arcuate and straight way portions, whereby as such sections are separated they will first open at the top and then move bodily away from one another, means for separating said sections and bringing them together again at intervals, 55 means to support said sections at a place as a pivot during the initial opening movement and while the sections are closed together, said means comprising mold fulcrum-lugs engaged beneath the lower ex-

tremities of the mold sections at their lower 65 meeting edges.

19. In cup pastry making machines of the type employing sectional female mold units and cores; the combination with a mold carrier, a pair of female mold sections, said carrier having guideways and said sections having members associated with said guideways, said guideways including arcuate and straight way portions, whereby as such sections are separated they will first open at 70 the top and then move bodily away from one another, means for separating said sections and bringing them together again at intervals, means to support said sections at a place as a pivot during the initial opening 75 movement and while the sections are closed together, said means comprising mold fulcrum-lugs engaged beneath the lower extremities of the mold sections at their lower 80 meeting edges.

85 said mold members that are associated with the slideways each comprising upper and lower rollers, the upper rollers resting on the bottoms of their respective slideways to sustain the female mold sections when closed, said lower rollers being out of operative engagement with the slideways when the mold sections are closed but adapted to come into operative engagement 90 after the mold sections have undergone their initial separatory movement.

95 20. In cup pastry making machines of the type employing sectional female mold units and cores; the combination with a mold carrier, a pair of female mold sections, said carrier having guideways and said sections having members associated with said guideways, said guideways including arcuate and straight way portions, whereby as such sections are separated they will first open at the top and then move bodily away from one another, means for separating said sections and bringing them together at intervals, said mold members that are associated with the slideways each comprising upper 100 and lower rollers, the upper rollers resting on the bottoms of their respective slideways to sustain the female mold sections when closed, said lower rollers being out of operative engagement with the slideways when the mold sections are closed but adapted to come into operative engagement after the mold sections have undergone their initial 105 separatory movement, said mold fulcrum-lugs on the carrier operatively associated with the female mold sections while closed 110 and during the initial separatory movement thereof.

115 21. In pastry making machines, a pair of female mold sections and a core therefor, a mold carrier, means for opening and closing said sections laterally, means to restrain the lower ends of the mold sections against separation until the upper ends have been 120

separated an initial distance, means to restrain the product from rising above the top plane of the mold sections after the core has been removed, and while the sections are being opened.

22. In pastry making machines, a pair of female mold sections and a core therefor, a mold carrier, means for opening and closing said sections laterally, means to restrain the lower ends of the mold sections against separation until the upper ends have been separated an initial distance, means to restrain the product from rising above the top plane of the mold sections after the core has been removed, and while the sections are being opened, said restraining means comprising a plate, means to mount said plate for up and down movement at a fixed place, means to hold said plate up until a mold unit from which the core has been removed is brought beneath the plate, and means to hold the plate down over the mold unit while the mold sections are being separated.
23. In pastry making machines, a pair of female mold sections and a core therefor, a mold carrier, means for opening and closing said sections laterally, means to restrain the lower ends of the mold sections against separation until the upper ends have been separated an initial distance, means to restrain the product from rising above the top plane of the mold sections after the core has been removed and while the sections are

being opened, means for varying the air pressure between the plate and the contents of the mold at intervals alternately to lower pressure below atmospheric and restore the same to atmospheric or greater, thereby alternately holding and releasing the article with respect to said plate.

24. In pastry making machines, a pair of female mold sections and a core therefor, a mold carrier, means for opening and closing said sections laterally, means to restrain the lower ends of the mold sections against separation until the upper ends have been separated an initial distance, means to restrain the product from rising above the top plane of the mold sections after the core has been removed, and while the sections are being opened, said restraining means comprising a plate, means to mount said plate for up and down movement at a fixed place, means to hold said plate up until a mold unit from which the core has been removed is brought beneath the plate, and means to lock the plate down over the mold unit while the mold sections are being separated, means for varying the air pressure between the plate and the contents of the mold at intervals alternately to lower pressure below atmospheric and restore the same to atmospheric or greater, thereby alternately holding and releasing the article with respect to said plate.

ALBERT E. DIETERICH.
